No. 821,515.

PATENTED MAY 22, 1906.

J. B. LINEBACK.
RAILWAY SIGNAL.
APPLICATION FILED DEC. 14, 1905.

UNITED STATES PATENT OFFICE.

JOHN B. LINEBACK, OF SILOAM SPRINGS, ARKANSAS, ASSIGNOR OF ONE-HALF TO ROBERT S. MORRIS, OF SILOAM SPRINGS, ARKANSAS.

RAILWAY-SIGNAL.

No. 821,515.

Specification of Letters Patent.

Patented May 22, 1906.

Application filed December 14, 1905. Serial No. 291,772.

To all whom it may concern:

Be it known that I, JOHN B. LINEBACK, a citizen of the United States, residing at Siloam Springs, in the county of Benton and State of Arkansas, have invented certain new and useful Improvements in Railway-Signals; and I do declare the following to be a full, clear, and exact description of the invention, such as will enable others skilled in the art to 10 which it appertains to make and use the same.

My invention relates to improvements in electric signals for railways.

The object of the invention is to provide an electric signal system of this character which will be simple in operation and inexpensive to install and by means of which train despatchers and operators, the engineers and crews of trains, and others along the track and at the stations between which a train is 20 moving will be notified of the approach of a train or trains and suitable signals may be sent from either station to the engineer on the moving train between them for the purpose of warning or notifying him of any danger.

With the above and other objects in view the invention consists of certain novel features of construction, combination, and arrangement of parts, as will be hereinafter described and claimed.

In the accompanying drawings, Figure 1 is a diagrammatic view of a portion of a single-track railway equipped with my improved electric signal system, and Fig. 2 is a similar 35 view showing a slightly-modified form of the system.

In the practice of my invention I arrange along the opposite sides of a railway-track T rows of lights 1, 2, which extend between adjacent stations A, B, and C along the line. Each of these rows of lights is included in an electric circuit 3, which extends from one station to the next adjacent station and which includes the conductors, the incandescent or 45 other electric lights, a switch 4, and an electric generator 5, which may be in the form of a dynamo, a dry or wet battery, or of any other form. One of the generators 5 is preferably provided at each of the stations, and 50 it is connected up with two of the electric circuits which lead in opposite directions from such station to the two next adjacent stations and which have their rows of lights arranged upon opposite sides of the track T.

If desired, the electric current may be supplied from an electric plant at places where there is such, and the dynamo or generator 5 may then be held in reserve for use in case of an emergency. The switch 4 may be of any desired form and construction and may be located in any desired point in or about the station, so that it may be readily operated by the train despatcher or operator, the conductors of the trains, or other officials at the station. While the lights 1, 2 may be of any 65 form and construction, I preferably employ the usual incandescent electric lamps and arrange them at suitable intervals, preferably one at about every half or quarter mile, and I also preferably have one located in or adjacent to the station, so as to be readily seen by persons who operate or have charge of the switch 4. This permits them to determine the condition of the track and to receive signals from the next adjacent station, as previously explained. By arranging the circuits as shown in the drawings, so that the two rows of lights leading in the opposite directions from each station are located upon op-

posite sides of the track, the engineer on moving trains will always have the row of lights leading from the station from which he is moving upon his left and the row of lights leading from the station toward which he is moving upon his right, thus permitting him 85 to readily distinguish whether there is danger ahead or in rear.

The operation of the system is as follows: Supposing the train should be at station B and headed toward station A, the conductor 90 of the train, the train-despatcher, or other designated official closes the switch 4 of the circuit leading from B to A before the train leaves B. As soon as this circuit is completed the lights 1 are illuminated, and the 95 one at station A informs the train-despatcher at that point that there is a train moving over the track from B to A. Should there be a train on the track moving from B to A, that fact will be indicated by the illumination of 100 the lights 2 in the circuit leading from station B to station A, and the engineer on the two trains will be warned. By opening and closing the switches 4 signals may be flashed over the electric circuit, so as to send messages of 105 warning to the train-engineers or the train-despatchers. Any code of signals may be devised for this purpose—for instance, a

2

steady light will indicate that a train is on the track between the two stations, a series of regular flashes indicate that a train has arrived at the station from which the signal is sent, a series of three broken flashes indicate that a train is following another from one station to the next, four broken flashes indicate that there is danger in the rear, and so on. Flashes, long and short, at different intervals may indicate any desired message which it might be desired to transmit from one station to the other or from one station to the engineer or other person upon the moving train. It will be understood that either white or red lights or lights of any other color may be used in this system.

In Fig. 2 of the drawings I have shown a double electric circuit extending from each station to the next adjacent station, and in one of the circuits is included a row of white lights 10 and in the other circuit a row of red or other colored lights 11. The row of white lights is used for transmitting signals such as the arrival of a train at the station from which the signal is sent, while the row of red lights is used where there is danger and it is desired to warn the engineers or train-dispatchers. A single switch 12 is employed for controlling both the red and white light circuits between each station, as will be readily seen upon reference to Fig. 2 of the drawings.

The use and advantages of the invention will be readily understood from the foregoing description, taken in connection with the accompanying drawings. It will be seen that collisions and other accidents may be rendered almost impossible by the use of this system. The train may be recalled at any point after leaving the station, and notice of a run-away engine or other danger along the track may be transmitted to the engineer or the crew on a moving train. It will also be

noted that the system is exceedingly simple to understand and operate, and owing to its simple construction the cost of installing it will be comparatively small.

Various changes in the form, proportion, and the minor details of construction may be resorted to without departing from the principle or sacrificing any of the advantages of this invention as defined by the appended claims.

Having thus described my invention, what I claim as new, and desire to secure by Letters Patent, is—

1. The combination with a railway-track and stations located at intervals therealong, of electric circuits extending from each of said stations in opposite directions toward the next adjacent stations and arranged upon opposite sides of said track, translating devices in said circuits arranged at intervals along said track and at the next adjacent stations, electric generators at said stations for supplying electric current to said circuits and switches for opening and closing said circuits.

2. The combination with a railway-track and stations located at intervals therealong, of electric circuits extending from each of said stations in opposite directions toward the next adjacent stations and arranged upon opposite sides of said track, electric lamps in said circuits at intervals along said track and at the adjacent stations, electric generators at said stations for supplying electric current to said circuits and switches in said circuits at said stations, substantially as described and for the purpose set forth.

In testimony whereof I have hereunto set my hand in presence of two subscribing witnesses.

JOHN B. LINEBACK.
